AUTOMATIC CIRCUIT BREAKER

Joseph Sachs, West Hartford, Conn., assignor to
 Colt's Patent Fire Arms Manufacturing Company, Hartford, Conn., a corporation of Connecticut

Application February 27, 1939, Serial No. 258,701

3 Claims. (Cl. 200—122)

This invention relates to a circuit breaker of the general type disclosed in my Reissue Patent No. 20,018 and in my Patent No. 2,020,333, each entitled Automatic circuit breaker. In a circuit breaker of the said type there is a bodily movable current-carrying bi-metallic latch which serves as at least a part of the mechanical connection between the handle or operating member and the movable contact carrying member.

5 In order to keep manufacturing costs at a minimum it is desirable to use one size and style of mechanism for a relatively wide range of electrical capacities. The electrical capacity of the circuit breaker can be widely varied by changing the size and characteristics of the movable bimetallic latch, but there are definite limits as to the minimum size of the latch inasmuch as the latch must in any event have sufficient mechanical strength to operate and control the movable

10 contact member.

When a circuit breaker of relatively large size is to be given a very small current capacity, it may be difficult or impossible to provide a bimetallic latch which is sufficiently strong mechanically and which is at the same time sufficiently sensitive to be heated and deflected by a relatively small overload current. The general object of this invention is to provide a circuit breaker which avoids the difficulties above pointed out, this being accomplished by changing the electrical connections so that no current passes through the bi-metallic latch itself, the said latch being heated solely by a separate current-carrying heating element closely adjacent thereto. This makes it possible for the latch to be relatively large to provide the required mechanical strength, the heating element being so designed as to effect heating as the result of a relatively small overload current.

40 In the accompanying drawing I have shown one suitable embodiment of the invention, but it will be understood that the drawing is intended for illustrative purposes only and is not to be construed as defining or limiting the scope of the invention, the claims forming a part of this specification being relied upon for that purpose.

Of the drawing:

Fig. 1 is a front view of a circuit breaker embodying the invention.

Fig. 2 is a view similar to Fig. 1, but with the front insulating cover omitted.

Fig. 3 is a transverse sectional view taken along the line 3—3 of Fig. 4.

55 Fig. 4 is a longitudinal sectional view taken

along the line 4—4 of Fig. 2 but including the cover, this view showing the movable parts in their closed-circuit positions.

Fig. 5 is a detail view of the heating element.

Fig. 6 is a fragmentary view similar to Fig. 4, but showing the movable parts in the positions which they occupy at the beginning of the automatic circuit-opening operation.

Fig. 7 is a view similar to Fig. 6, but showing the movable parts in different relative positions.

Referring to the drawing, 1 represents the main insulating base or support which carries all of the other parts of the circuit breaker. Fitting the support 1 at the front thereof is an insulating cover 2. The rear support 1 is of box-like form, being substantially closed at all four sides and at the bottom. The front cover is also of more or less box-like form, having a recess open at the bottom into which certain parts of the mechanism project. When the two parts 1 and 2 are assembled as shown, there is provided an interior recess which contains all of the operative parts of the circuit breaker other than the handle.

Carried by the rear support 1 near the front thereof are two forward projecting parallel metallic plates 3, 3 which are held in place by means of screws 4, 4 extending forward from the rear of the support. The plates 3, 3 are provided with integral rearward extending portions 3^a, 3^a. Carried by the said rearward extensions 3^a, 3^a and extending transversely between them is a pivot pin 5. Pivotedly mounted on the pin 5 is a contact carrying member which includes two parallel plates 6, 6 spaced apart transversely and 35 suitably connected together to move as a unit. These plates have aligned bearing apertures through which the pivot pin 5 extends, shoulders on the pin serving to hold the plates in proper spaced relationship. Suitable spacing 40 washers, not shown, hold the plates in proper spaced relationship to the supporting plate extensions 3^a, 3^a.

The two plates 6, 6 serve to carry the main movable contacts 7 and 8 of the circuit breaker, 45 each of which extends from one to the other of the two plates 6, 6 and is in direct engagement with both of them. Each of the said plates 6 is provided with apertures adapted to receive similarly shaped lateral projections on the corresponding contact. When the said projections on the contacts are entered in the said apertures of the two plates, the contacts are firmly held in proper predetermined relationship.

The two plates 6, 6 are additionally connected 55

and held in spaced relation by means of insulating members 9 and 10 which are structurally separate from the plates. The plates are notched to receive projections 11, 12, 13 and 14 formed 5 on the insulating members and the two plates and the insulating members are held in proper relationship by means of tie rods or rivets 15, 15. The plates 6, 6 have arcuate outer edges concentric with the pivotal axis at 5 and the insulating members 9 and 10 are externally shaped 10 to conform to these arcuate edges. It will be apparent that the insulating members 9 and 10 extend transversely from plate to plate and that the movable contact 7 extends through the space 15 between the two members. The member 9 engages with the other movable contact 8 and thus extends circumferentially from one contact to the other.

Carried by the movable contact member is a 20 bi-metallic thermostatic strip 16 and this is shown as being connected directly with the contact 7, but there may be variation as to the manner of mounting or attaching the said strip. The strip 16 is provided at its projecting end with a lug 17 which enables the strip to serve as a latch 25 as will be presently explained.

A heating element 18 is provided which electrically connects the two movable contacts 7 and 8. This is preferably a wire bent to a serpentine form as shown in Fig. 5, and it is positioned 30 closely adjacent the strip or latch 16, so that heat from the element 18 is transmitted to the latch.

Carried by the insulating support 1 are two 35 substantially stationary main contacts 19 and 20 which are connected with the said support by means of more or less resilient bent conducting straps 21 and 22. These stationary contacts 19 and 20 are so positioned and arranged that 40 they can be firmly engaged respectively by the two movable contacts 7 and 8 as clearly shown in Fig. 3. The outer end of the supporting strap 21 engages the bottom wall of a recess in the support 1 and the said strip is held in place by 45 means of two screws 23 which also hold a conductor 24. This conductor projects from the circuit breaker at the right and may be connected at 24a directly with the bus bar of a panel board or may be provided with a suitable wire 50 engaging terminal. A rearward projection 2a on the cover 2 normally substantially fills the last said recess in the main support. The outer end of the conducting strap 22 engages the bottom wall of a recess in the main support 1 and 55 is held in place by screws 25 which also hold a laterally extending conductor 26. The conductor 26 is provided with a wire terminal 26a and suitable recesses 27 are formed in the upper left hand corners of the support 1 and of the cover 60 2 to permit access to the said wire terminal. A separate insulating block 28 normally substantially fills the last said recess in the main support.

From the foregoing description it will be apparent 65 that pivotal movement of the contact member serves to bring the movable contacts 7 and 8 into or out of engagement with the respective stationary contacts 19 and 20 to make or break the circuit. When the parts are in the 70 contact engaging position as shown in Fig. 4 electrical connection is established between the conductor or terminal 24 and the terminal 26a. Springs 29, 29 are provided for biasing the member in the contact disengaging or circuit-opening 75 direction, these springs surrounding the pin

5 and being positioned between the supporting plate extensions 3a, 3a and the insulating plates 6, 6.

For actuating the contact member for normal switching purposes or to effect closing of the 5 circuit after automatic opening thereof, there is provided an actuating member or actuator 30, which is normally engaged by the thermostatic strip or latch 16. The actuator 30 is pivoted to the contact member for movement about a bodily 10 movable axis, and it is of bell crank form and consists of two spaced metallic plates pivotally mounted on a pin 31 extending transversely between the two side plates 6, 6. A transverse pin 15 32 serves to limit relative movement of the actuating member in the counter-clockwise direction. The actuating member is provided with a transverse pin or roller 33 which, at normal 20 temperatures, is engaged by the lug 17 on the thermostatic latch 16. With the parts in the 25 relative positions shown in Fig. 4, the actuator and the contact member are positively connected to move in unison.

For manually operating the actuator 30 I provide 25 a handle member 34 which is mounted on a pin 35 extending transversely between the supporting plates 3, 3. The handle member projects through a suitable opening in the front wall of the front cover 2. A spring 36 is provided 30 which serves to bias the handle toward its open-circuit position, that is, in the counterclockwise direction from the position shown in Fig. 4. The handle member 34 is connected with the actuator 30 by means of two similar links 37, 37, the links being pivoted to the handle members at 38 and 35 to the actuator at 39.

When the parts are in the relative positions shown in Fig. 4 the links 37 cooperate with the handle member 34 to form a toggle which locks the parts in position with the movable contacts 40 7 and 8 pressed into firm engagement with the stationary contacts 19 and 20. Continued movement of the handle in the clockwise direction is prevented by the engagement of an extension 34a thereon with a pin 40 extending transversely 45 between the plates 3, 3. The pivotal axis at 38 is above a straight line connecting the pivotal axes at 35 and 39, and thus the handle member 34 and the links 37 serve to resist the tendency of the contact member to move in the clockwise 50 direction under the influence of the springs 29 and of the resilient contact supporting strips 21 and 22. At the same time the said toggle action holds the handle 34 in its right hand or closed-circuit position, resisting the tendency of 55 the spring 36 to move the handle member in the counter-clockwise direction.

The above-described toggle action can be released by pressing the handle toward the left, the parts then moving under the action of the 60 springs 29 and 36 to their open-circuit positions. The movable contacts 7 and 8 are thus disengaged from the stationary contacts 19 and 20 and the circuit is broken in two separate places. By moving the handle toward the right the several parts 65 can be restored to their respective positions, as shown in Fig. 4, and the circuit can be thus re-established.

As already explained the heating element 18 is electrically connected between the contacts 7 70 and 8 and is adjacent the latch 16. Upon the attainment of an excess current condition in the circuit which causes more than normal heating of the element 18, the latch 16 is deflected downward or outward, with the result that the 75

lug 17 is disengaged from the pin or roller 33, such disengagement being shown in Fig. 6. This disengagement or partial disengagement permits the actuator 30 to turn slightly relatively to the contact member and in the clockwise direction. This slight clockwise movement reduces the pressure which had theretofore served to hold the links 37 and the handle member 34 in their effective toggle relationship. This reduction in pressure permits the handle member 34 to move in the counter-clockwise direction so as to render the toggle ineffective. By reference to Fig. 6 it will be observed that the pivotal axis at 38 has moved below the dot-and-dash line connecting the pivotal axes at 35 and 39, thus freeing both the contact member and the handle member so that they are automatically moved to their open-circuit positions under the influence of the springs 29 and 36. It will be understood that the contact member and the handle member move substantially simultaneously, the lug 17 and the pin or roller 33 perhaps never becoming completely disengaged from each other. When the parts reach their full open-circuit position, the lug 17 and the pin or roller 33 can freely re-engage as soon as the thermostatic strip 16 has sufficiently cooled.

The described circuit-opening movement of the contact member is not in any way dependent on the circuit-opening movement of the handle member and will, in fact, occur even though the handle member be held in its closed-circuit position, as shown in Fig. 7. The downward or outward deflection of the thermostatic strip 16 permits the actuator 30 to turn in the clockwise direction as already stated, thus releasing the contact member from the control of the handle member 34 and of the links 37. The contact member moves in the clockwise direction to the position shown in Fig. 7, the actuator 30 and the links 37 assuming the relative positions shown in that figure. If the handle 34, after having been held as described, be now released, it will move under the influence of the spring 36 to its open-circuit position, thus bringing the actuator 30 into its normal position with respect to the contact member so that the pin or roller 33 can be engaged by the lug 17.

While the latch 16 may be electrically connected with the contact 7 as shown, this is merely to facilitate manufacture, and inasmuch as there is no electrical connection with the other end of the latch, no current flows therein. The latch can be of such size as to have ample mechanical strength. The heating element 18 may have a very high resistance so as to be heated to a high temperature by even a rather small overload current.

What I claim is:

1. The combination in an automatic circuit breaker, of a movable contact member biased in the circuit-opening direction and including an electric contact, a stationary electric contact engageable by the movable contact, releasable

mechanism normally holding the contact member in closed-circuit position, a bodily movable thermostatic bi-metallic strip forming part of said mechanism and rigidly connected at one end with the movable contact member and capable of deflection to cause the other end to relatively move and thereby effect the release of the mechanism, and a bodily movable heating element separate from the bi-metallic strip and electrically connected with said movable contact 10 and positioned closely adjacent the bi-metallic strip so that upon the attainment of an abnormal current condition in the circuit the heating element transmits sufficient heat to the strip to cause deflection thereof relative to said heating 15 element and releasable mechanism to effect release of said mechanism.

2. The combination in an automatic circuit breaker, of a movable contact member biased in the circuit-opening direction and including two spaced electric contacts, two stationary electric contacts engageable by the respective movable contacts, releasable mechanism normally holding the contact member in closed-circuit position, a bodily movable thermostatic bi-metallic strip forming part of said mechanism and rigidly connected at one end with the movable contact member and capable of deflection to cause the other end to relatively move and thereby effect the release of the mechanism, and a bodily 30 movable heating element separate from the bi-metallic strip and electrically connecting the two contacts and positioned closely adjacent the bi-metallic strip so that upon the attainment of an abnormal current condition in the circuit the heating element transmits sufficient heat to the bi-metallic strip to cause deflection thereof relative to said heating element and releasable mechanism to effect release of said mechanism.

3. The combination in an automatic circuit breaker, of a movable contact member biased in the circuit-opening direction and including two spaced electric contacts, two stationary electric contacts engageable by the respective movable contacts, a heating element electrically connecting the movable contacts and bodily movable therewith and with the movable contact member, releasable mechanism normally holding the contact member in closed circuit position, a thermostatic bi-metallic strip independent of said heating element rigidly connected at one end with the movable contact member for bodily movement therewith, said thermostatic bi-metallic strip being disposed in proximity to the heating element with its major portion free to move relative to said heating element when deflected upon attainment of abnormal current conditions in the circuit, and the other end of said bi-metallic strip being operatively engageable with the releasable mechanism whereby the 60 bi-metallic strip forms a part thereof to effect releasing movement of the mechanism upon deflection of said strip.

JOSEPH SACHS.
